(57) **CLAIM**

The ornamental design for a light as shown and described.

DESCRIPTION

FIG. 1 is a top perspective view of a light illustrating my new design.

FIG. 2 is a bottom perspective view.

FIG. 3 is a top view.

FIG. 4 is a bottom view.

FIG. 5 is a front view.

FIG. 6 is a rear view.

FIG. 7 is a right-side view; and,

FIG. 8 is a left-side view.

Portions of the light are shown in broken lines. Portions shown in broken lines form no part of the claimed design. The break lines in the drawings indicate that the appearance of any portion of the Light between the break lines forms no part of the claimed design.

1 Claim, 8 Drawing Sheets(56)
